(57) **CLAIM**

The ornamental design for a seat with feet as shown and described.

DESCRIPTION

FIG. 1 is a perspective view of a seat with feet of the new design;

FIG. 2 is a front elevational view of the seat with feet of FIG. 1;

FIG. 3 is a rear elevational view of the seat with feet of FIG. 1;

FIG. 4 is a left side elevational view of the seat with feet of FIG. 1, the right side elevational view being a mirror image thereof;

FIG. 5 is a top plan view of the seat with feet of FIG. 1; and, FIG. 6 is a bottom plan view of the seat with feet of FIG. 1. The broken lines are included for the purpose of illustrating portions of the article and form no part of the claimed design.

1 Claim, 4 Drawing Sheets
